UNITED STATES PATENT OFFICE.

WILLIAM RUMBLE, JR., OF CRANFORD, NEW JERSEY.

DESIGN FOR A BUCKLE.

45,540.

Specification for Design.

Patented Mar. 31, 1914.

Application filed January 7, 1914. Serial No. 810,878. Term of patent 3½ years.

To all whom it may concern:

Be it known that I, WILLIAM RUMBLE, Jr., a citizen of the United States, residing at Cranford, in the county of Union and State of New Jersey, have invented a new, original, and ornamental Design for a Buckle, of which the following is a specification, reference being had to the accompanying drawing, forming part thereof.

The figure is a perspective view of a buckle, covering my new design.

I claim:

The ornamental design for a buckle, as shown.

WILLIAM RUMBLE, JR.

Witnesses:

E. M. FRINT,
F. F. HUNT.
